UNITED STATES PATENT OFFICE

WILLIAM C. HEALD, OF BELLOWS FALLS, VERMONT

AUTOMATIC VOLTAGE CONTROLLER

Application filed September 25, 1929. Serial No. 395,098.

This invention appertains to new and useful improvements in transformer controllers for electricity distribution systems.

The primary object of this invention is to provide automatic means whereby a current distributing line may be built up upon a decrease in its voltage.

During the course of the following specification and claims, numerous important objects and advantages of the invention will readily become apparent to the reader.

In the drawing:

The single view represents a diagram of the novel automatic voltage controller.

Referring to the drawing, wherein like numerals designate like parts, it will be observed that a pair of relays are denoted generally by A and B.

Numerals 5 and 6 designate the two sides 20 of a current distributing line, while numeral 7 represents generally a transformer of the type especially adapted for use in conjunction with this invention.

Each of the relays includes a core 8 with 25 a coil 9 wound thereon, the core being movable and connected to a pivotal beam 10 through the agency of a pivotal link 11. As is clearly shown in the drawing, each beam is pivotally supported as at 12 and has an 30 extension 13 carrying the means 14. This means 14 may include a spring (not shown) for normally maintaining the beam in an upward position at its free end.

A dashpot 15 is provided adjacent the 35 free end of the respective beam to retard the action thereof. Each beam is also equipped with a block 16 at its free end for bridging either the contacts 17 and 18' or the contacts 19 and 18 as the case may be.

The transformer 7 includes a core 20, a primary winding 21 and a secondary winding 22 which has an intermediate tap from which the lead 23 extends. One side of the secondary winding is connected by means of 40 the conductor 24 to the contact 18 of the relay B, while the opposite side of the secondary winding is connected by way of the wire 25 to the contact 18' of the relay A. The tap wire 23 is connected to the contact 45 17 of the relay B, while the contact 18' of

the relay B is connected by way of the wire 26 to the line 6 of the distribution line. The contact 19 of the relay B is also connected to the negative line 6 of the line.

The contact 17 of the relay A is connected by way of the wire 27 to the line 5 of the distribution line while one side of the transformer primary winding 21 is likewise connected through the agency of the conductor 28 to line 5. The opposite line of 60 the primary winding is connected by way of the conductor 29 to the line 6 of the distribution line. It will also be noted that the contact 18' of the relay A is connected by the jumper 30 to the line 5 of the line, as is 65 the contact 19.

The system is normal, when lines 5 and 6, and both relays A and B have their blocks 16 engaged with contacts 17 and 18'.—Block 16 of relay A bridges contacts 17 and 18' and completes the line 5 and it can be seen that contacts 18 and 19 of relay A open the circuit of the lead 25 and relay B being in the position as above described, leaves contacts 18 and 19 unbridged, thus leaving the circuit of 70 wire 24 from the other side of the secondary winding to the line 6 open.

Although the primary is across the lines 5 and 6, no transforming action can be completed by the secondary. When the potential 80 falls across lines 5 and 6, relay A does not have sufficient magnetic pull to retain its position and is pulled by gravity to bridge contacts 18 and 19, while relay B retains its former position. This operation of relay A 85 breaks the circuit of line 5 and closes the secondary lead 25. It is obviously shown that the voltage is stepped up by the use of a portion of the secondary winding establishing a circuit from line 5 to contact 19, to contact 18 of relay A, from there through wire 23 to contact 17 and from there to contact 18' of relay B and then to the line 6.

As the potential decreases further, relay B 90 becomes insufficiently energized and block 16 is pulled by gravitation to contacts 18 and 19 which opens the circuit of wire 23 and closes it to the full secondary winding 22 which extends from the line 5 through contacts 18 and 19 of relay A through winding 22 and wire 100

24 and through contacts 18 and 19 of relay B to the line 6.

Manifestly, the foregoing invention provides means for always maintaining a voltage within certain limitations and this is through the agency of automatic means.

Having thus described the invention, what is claimed as new is:

- 10 1. An automatic voltage regulator for distribution lines comprising a transformer having a primary and a secondary winding, an opening in one of the distribution lines, the primary winding of said transformer being connected across the distribution lines on the supply side of the opening, electromagnetic means for closing said lines at a predetermined voltage and upon a decrease in voltage to open said line and connect one side of the secondary winding to one of the distribution lines, and a second electro-magnetic means adapted upon the decrease in line voltage to connect a tap of the secondary winding to the other distribution line and upon a further decrease in voltage to connect the other terminal of the secondary winding to the other distribution line.
- 20 2. An automatic voltage regulator for electrical distribution lines, comprising a transformer having a primary and a secondary winding, one of said distribution lines having an opening therein, the primary winding of the transformer being connected across said distribution lines, on the supply side of the opening in the line, a relay having a winding connected across said distribution lines on the supply side of the opening, a second relay connected across the distribution line on the supply side of the opening, a circuit maker and breaker controlled by the first named relay for normally closing the line at a predetermined voltage and adapted upon a decrease in voltage to open said line, a second circuit maker and breaker controlled by said relay and connected in series with one terminal of the secondary winding and to one of the distribution lines and adapted upon the decrease in voltage to close and connect the said secondary winding terminal to the distribution line, a circuit maker and breaker controlled by the second named relay and connected in series with a tap of the secondary winding and the outer distribution line and adapted upon the decrease in voltage to connect the tap to the distribution line and a second circuit maker and breaker controlled by the second relay and connected in series with the other terminal of the secondary winding and the other distribution line and adapted upon a further decrease in voltage to connect the terminal of the secondary winding to the other distribution line.

In testimony whereof I affix my signature.
WILLIAM C. HEALD.
